UNITED STATES PATENT OFFICE.

MILO CRAWFORD, OF SPRINGFIELD, MISSOURI.

HEADLIGHT-DIMMER.

1,311,951.

Specification of Letters Patent. Patented Aug. 5, 1919.

Application filed March 27, 1918. Serial No. 224,988.

To all whom it may concern:

Be it known that I, MILO CRAWFORD, a citizen of the United States, residing in the city of Springfield, county of Greene, State of Missouri, have invented new and useful Improvements in Headlight-Dimmers, of which the following is a specification, reference being had to the accompanying drawings.

10 This device pertains to headlight dimmers for use upon automobiles, locomotives, street-cars, or, in fact, wherever a headlight may be employed.

The primary object of the invention is to 15 provide a dimmer of a shutter pattern, wherein two oppositely disposed shutters are adapted to close together at the front, either partially or fully, over the headlight, as may be desired, the degree of closure being 20 readily controlled by a control rod extending back to the hand of the driver.

A further object is the production of a 25 device of this character in a simple, practical, efficient and economical form, best adapted for the uses and purposes intended.

With these and other objects in view, attention is called to the accompanying drawings; wherein -

Figure 1 is a frontal elevation showing 30 my dimmer with the shutters closed;

Fig. 2 is a frontal elevation showing the dimmer with the shutters partially opened;

Fig. 3 is a sectional side elevation;

Fig. 4 is a plan view;

35 Figs. 5, 6 and 7 are details showing the working elements of my device.

Referring more particularly to the drawings, my invention resides primarily in two oppositely disposed curved shutters 1 and 1', 40 each shutter being mounted upon its respective horizontal base plate 2 and 2', said base plates being curved at their outer peripheries to conform to the curvature in said shutters, and said shutters being so positioned upon said base plates that their line 45 of curvature would extend in a horizontal direction, whereby the adjacent edges 3 and 3' of said shutters 1 and 1' may be brought 50 frontally together on a straight vertical line, as shown in Fig. 1. The base plates 2 and 2' are pivoted upon the common pivot 4 positioned in the center of the bottom 5 of the casing 6. The base plates 2 and 2' are extended each beyond the pivot 4, so as to 55 form lever arms 7 and 7', and to the ends of these lever arms 7 and 7' are pivoted at the

points 8 and 8' the links 9 and 9', same converging rearwardly where they are pivoted to the control rod 10 at the common point 11. Coil springs 12 and 12' engage at their forward ends the base plates 2 and 2', and at their rearward ends the casing 6, their effect being to draw back and normally hold in open position the base plates 2 and 2' and the shutters 1 and 1' carried thereby. The 60 control rod 10 extends back into the body of the car and is pivoted to the lug 13, which in turn is rigidly joined to the journaled base rod 14. A lever 15 likewise joined to said base rod 14 and working in connection with 65 the pawl 16 and ratchet 17, enables the operator readily to open or close the dimmer. The upper ends of said shutters 1 and 1' may be fitted to and held by top plates 2^a and 2'^a corresponding to the base plates 2 70 and 2', and likewise being pivoted together and to the supporting bracket 22-22' at the common point 4^a. This bracket 22-22' is disposed to the rear of the headlight so as not to interfere with the same. The shutters 1 may be made entirely of celluloid or 75 frontal half circles of celluloid 18 and 18' may be employed, and the balance of the shutters filled in with heavy cloth 19-19' or any other suitable material. The bracket 80 22-22' is pierced with the hole 20, through which from the rear is introduced the ordinary electrical connections for the frontal headlight bulb 21 and from which may be supported the ordinary headlight as indicated in dotted lines in Fig. 3 of the drawings. The shutters 1 and 1' are disposed to 85 either side of said bulb 21 and the headlight so supported by said bracket, same closing together in front of said bulb 21, or 90 opening to either side thereof by operation of the control lever 10. Additional control levers, as 10' may be provided, one each for 95 each headlight employed. The apparatus may be constructed so that the shutters 1 100 and 1' will close on a horizontal frontal line, if preferred, instead of on a vertical line, as shown. Suitable brackets, posts, bolts and screws are, of course, utilized for 105 mounting the apparatus in operative position.

While I have herein described and set forth a certain specific manner and method of constructing the elements of my invention, it is understood that I may vary from 110 the same in minor details, not departing from the spirit of my invention, so as best

to construct a practical device of the class described.

In operation, the headlight and elements are mounted in proper operative position upon the vehicle. When the hand lever 15 is thrown forwardly, the shutters 1 and 1' are pulled open by the springs 12 and 12', whereby a full glow of light is projected ahead. When the lever 15 is drawn back-
wardly, said shutters 1 and 1' are pulled together at the front, whereby the light ray is narrowed as much as desired, or may be cut off altogether. When the shutters are entirely closed, a diffused glow of light will
nevertheless be transmitted through the translucent fronts of said shutters.

What I claim to be new and patentable is:

1. A headlight dimmer comprising a pair of curved shutters located opposite each other when open and movable toward each other to a closed position, said shutters having semi-circular frontal translucent portions, a layer of cloth covering the remaining portions of each of the curved shutters,

means for pivoting the shutters, and means 25 for opening and closing the shutters.

2. A headlight dimmer comprising a pair of curved shutters located opposite each other when open and movable toward each other to a closed position, a vertically disposed approximately U-shaped bracket having upper and lower arms and a vertical connecting portion adapted to be arranged in rear of and form a support for a headlight and provided adjacent one of its arms 30 with a guide opening, vertically aligned pivots located at the upper and lower arms and connecting the shutters to the said bracket and supporting the said shutters for pivotal movement, an operating rod extending 35 through the guide opening of the bracket, and means for connecting the operating arm with the shutters for enabling the latter to be actuated simultaneously by the said rod.

MILO CRAWFORD.
